Patented Sept. 8, 1914.

UNITED STATES PATENT OFFICE.

JAMES M. ROSE, OF PHILADELPHIA, PENNSYLVANIA, ASSIGNOR TO MERCHANT & EVANS COMPANY, OF CAMDEN, NEW JERSEY, A CORPORATION OF NEW JERSEY.

UMBRELLA-STAND.

1,109,788.

Specification of Letters Patent.

Patented Sept. 8, 1914.

Application filed March 20, 1912. Serial No. 685,022.

To all whom it may concern:

Be it known that I, JAMES M. ROSE, a citizen of the United States, residing in Philadelphia, Pennsylvania, have invented certain Improvements in Umbrella-Stands, of which the following is a specification.

One object of my invention is to provide a structure particularly adapted to support a series of elongated objects such as umbrellas, canes or the like, which shall be so made that when desired it may be collapsed in order to permit of its storage or transportation with the utmost convenience; the arrangement of parts being such that when so collapsed it shall occupy but relatively little space.

I further desire to provide a stand or holder having the above noted characteristics, which shall be simple and substantial as well as relatively inexpensive.

These objects and other advantageous ends I secure as hereinafter set forth, reference being had to the accompanying drawings; in which,

Figure 1 is a perspective view of a stand constructed according to my invention, the parts being illustrated as in their extended positions ready for use; Fig. 2 is a perspective view showing the stand of Fig. 1 with its parts in their collapsed or nested positions; and Fig. 3 is a vertical section illustrating the detail construction of the lower part of the container forming the base.

In the above drawings, 1 represents the base of the stand which is preferably formed as a shallow box having a bottom section 2, side sections 3 and end sections 4. Fixed to the bottom section 2, adjacent to but spaced away from the end sections 4 are two pairs of knees or short angles 5, which are rigidly and permanently connected to the bottom section by riveting or otherwise so that each of them has one part whose flat face is substantially parallel with the adjacent face of an end section.

The upper part of the stand consists of an open rectangular frame 6 made of sheet metal of suitable stiffness and of such outside dimensions as to fit within the base or container 1, its height being such that when placed within said container its upper edges are substantially flush with the top thereof. This frame 6 is braced and at the same time subdivided into a number of umbrella re-

ceiving spaces, by means of a central longitudinally extending bar 7, extending between its end members and any desired number of bars 8 connecting the side members. Hinged to the opposite ends of the frame 6 are a pair of relatively stiff frame supporting members made of bar material and U-shaped in outline, each consisting of two side members 9 and a bottom member 10. The upper ends of each of the side members are preferably bent toward each other and mounted in suitable bearings 11 on the side of the end members of the frame 6 so as to be free to return therein. The bottom members 10 of these supporting structures are of such length that the side members 9 with said bottom members easily fit between the side members of the frame 6, and the angle pieces 5 are spaced away from the ends 4 of the container 1 such a distance that said bottom members 10 tightly fit between them and said ends 4. With this arrangement of parts, when the device is desired for use, the frame supporting members are extended in the positions shown in Fig. 1 substantially at right angles to the general plane of the frame 6, and the bottom members 10 are each inserted between one of the ends 4 of the container 1 and the pair of angles 5 adjacent thereto. The stand thus formed is a relatively rigid structure since the side members 9 of the frame supporting structures are prevented from swinging outwardly partly by reason of the fact that their lower portions engage and are braced by said end members 4 while their opposite ends engage the end members of the frame 6.

When it is desired to collapse the stand for storage or transportation, the frame 6 with its supporting structures is pulled upwardly away from the container 1 so that the bottom members 10 of the said supporting structures are disengaged from the angles 5. Said supporting structures may then be turned in their bearings 11 through an angle of substantially 90 degrees so that they lie one over the other within the frame 6 which may then be placed within the container 1 in the nested position shown in Fig. 2.

Inasmuch as all of the parts of my stand may be made of relatively light and stiff sheet and bar material without impairing the rigidity and strength of the finished structure, the latter is comparatively light

in weight and by reason of the arrangement of parts described it is convenient to use and adjust, being particularly valuable for use in churches and halls where it may be conveniently collapsed after use with a view to storing it in a relatively small space.

I claim—

1. The combination in an umbrella stand of a relatively shallow container forming a base; an open frame formed to removably fit within the container; intersecting bars extending between opposite sides of the frame to form receiving compartments; means for supporting the frame at a distance above the container consisting of U-shaped rods having their ends hinged to said frame and foldable within the same; with means carried by the container for detachably engaging said supporting rods.
2. The combination in a stand of a con-

tainer; holding members fixed to the bottom of said container, each with a part spaced away from and substantially parallel with an end of the container; an open frame having receiving compartments; and supporting members movably connected to the frame so as to be capable of folding within the same or of extending substantially at right angles thereto, said supporting members removably fitting between the ends of the container respectively and the holding members adjacent thereto.

In testimony whereof, I have signed my name to this specification, in the presence of two subscribing witnesses.

JAMES M. ROSE.
